Blackwelder, Spec. - 3 Miss.

UNITED STATES PATENT OFFICE.

JAMES H. DAVIS, OF DAYTON, OHIO, ASSIGNOR TO GENERAL MOTORS RESEARCH CORPORATION, OF DAYTON, OHIO, A CORPORATION OF DELAWARE.

INTERNAL-COMBUSTION ENGINE.

Application filed July 19, 1923. Serial No. 652,556.

To all whom it may concern:

Be it known that I, JAMES H. DAVIS, a citizen of the United States, and a resident of Dayton, county of Montgomery, and State of Ohio, have invented certain new and useful Improvements in Internal-Combustion Engines, of which the following is a full, clear, concise, and exact description, such as will enable others skilled in the art to which the invention relates to make and use the same, reference being made therein to the accompanying drawings, which form a part of this specification.

This invention relates to internal combustion engines and is illustrated as embodied in an engine for a tractor or other self-propelled vehicle.

An object of the invention is to provide for exhausting the crank case of the engine to remove therefrom moisture and combustible vapors, and atomized particles of fuel and lubricanting oil, to minimize condensation and dilution of the lubricating oil in the crank case. As one means of achieving this object the crank case may be connected with engine-operated means, such as the fuel intake device, for effecting a flow of fluid in such a manner as to cause suction in the connections from the crank case. In the arrangement shown in the drawing the connections from the crank case are operated by being connected to the air intake of the carburetor. Preferably the connections are arranged between the carburetor and the air cleaner, and I consider it desirable also that air from the cleaner should be supplied to the crank case to provide a circulation therethrough and back to the carburetor which will effectively sweep out the combustible gases and atomized fuel and oil.

From a slightly different point of view the invention may be regarded as providing for exhausting the crank case by means of an outlet which is connected to a pipe through which a stream of fluid is passing, to apply suction to the crank case connection on the ejector principle. Another feature of the invention in the illustrated form relates to arranging an air inlet to the crank case having a portion projecting into the conduit between the air cleaner and the carburetor, in such a manner that the stream of air sets up a pressure in the crank case con-

nection tending to feed the cleaned air therethrough. 55

The above and other objects and features of the invention, including various novel combinations of parts and desirable particular constructions, will be apparent from the following description of the illustrative embodiment shown in the accompanying drawing, in which the figure is a top plan view, partly broken away, of an internal combustion engine equipped with means for exhausting the crank case as above described. 65

In the drawing the engine is indicated at 10 and the radiator at 12, the engine being supported on a crank case 14 and supplied with a combustible mixture of air and fuel through an intake device 16 which includes a carburetor 18 supplied with air from a cleaner 20 through a conduit 22. The fuel is controlled by any suitable throttle control device 24. The above described parts may be, except as described below, of any desired construction and are therefore not particularly illustrated but merely shown in conventional forms. 70

According to the present invention, the conduit 22 is connected to the crank case 14 by a pipe 26 leading from the front end of the crank case, and exhausting into the conduit 22 at its rear end which is flush with the side of the conduit 22. By this arrangement the suction of the fuel intake device, and the ejector effect of the stream of air in the conduit 22, combine to suck air from the crank case through the connection 26. To provide a circulation of clean air for this purpose, I prefer that the crank case be further connected with the conduit 22 by a connection 28 which projects into the conduit 22 at its front end and which opens into the crank case at its rear end. Thus the stream of air in the conduit 22 sets up a pressure in the connection 28 tending to feed a part of the cleaned air therethrough into the crank case, this pressure being in addition to the suction operating on the connection 26. By this arrangement it will be seen that there is a constant circulation of air from the cleaner 20 through the crank case 14 to the carburetor 18 which will effectively remove from the crank case all moisture and combustible vapors, atomized particles of fuel, and oil. 105

2
While one embodiment of my invention has been illustrated and described it is not my intention to limit its scope to that embodiment or otherwise than by the terms of the appended claims.

I claim:

1. An internal combustion engine comprising, in combination, a crank case; a conduit for the flow of a stream of fluid, and a connection from the crank case projecting through the conduit and facing toward the direction from which the fluid flows in such a manner that a part of the fluid flows through the connection to wash out moisture and combustible gases and atomized particles of fuel and oil from the crank case.
2. An internal combustion engine comprising, in combination, a crank case, an air conduit, means operated by the engine for causing a flow of air through the conduit, and a connection from the conduit to the crank case which projects into the conduit in the opposite direction to the flow of air so that part of the air tends to pass into the crank case.
3. An internal combustion engine comprising, in combination, a crank case, a conduit, means operated by the engine for causing a flow of fluid through the conduit, and a pair of connections from the crank case to the conduit, one of which opens into the conduit in the direction of the flow of fluid therein so that the fluid by its flow exerts a suction on the connection, and the other of which opens into the conduit in the opposite direction and projects into the conduit so that part of the fluid tends to flow through said connection into the crank case,

by which arrangement there is a circulation of fluid from the conduit through the crank case and back to the conduit.

4. An internal-combustion engine comprising a crank case, an air intake conduit leading from atmosphere to the fuel intake of the engine, and plural conduits connecting said crank case and said air intake conduit for causing circulation through said crank case and intake conduit.

5. An internal-combustion engine comprising a crank case, an air intake conduit leading from atmosphere to the fuel intake of the engine, and plural conduits between said crank case and said air intake conduit, one of said plural conduits having the end that connects with the air intake conduit facing in a direction opposite to the flow of air therein.

6. An internal-combustion engine comprising a crank case, an air intake conduit leading from atmosphere to the fuel intake of the engine, an air cleaner in said air intake conduit, and plural conduits connecting said crank case with said intake conduit at points between said air cleaner and the fuel intake of the engine.

7. An internal-combustion engine comprising a crank case having an air inlet and a separate outlet for air and vapors, an air intake conduit leading from atmosphere to the fuel intake of the engine; and an air cleaner in said air conduit, said air inlet communicating with the air intake between the air cleaner and the fuel intake of the engine.

In testimony whereof I affix my signature.
JAMES H. DAVIS.
